[57] CLAIM

The ornamental design for a barber's clipper holder, as shown and described.

DESCRIPTION

FIG. 1 is a front view of a barber's clipper holder embodying my design;

FIG. 2 is a top plan view of the design as seen in FIG. 1; FIG. 3 is a left side elevational view of the design as shown in FIG. 1;

FIG. 4 is a right side elevational view of the design as shown in FIG. 1;

FIG. 5 is a rear view of the design as shown in FIG. 1; FIG. 6 is a top, front right side perspective view of the design as shown in FIG. 1; and,

FIG. 7 is a bottom plan view thereof.
